(57) **CLAIM**

The ornamental design for sample dilution container, as shown and described.

DESCRIPTION

FIG. 1 is a perspective view of the sample dilution container;
FIG. 2 is a front view thereof;
FIG. 3 is a rear view thereof;
FIG. 4 is a top plan view thereof;
FIG. 5 is a bottom plan view thereof;
FIG. 6 is a left side view thereof, the right side view appears symmetrical with the left side view;
FIG. 7 is a cross-sectional view taken along line 7-7 of FIG. 2;
FIG. 8 is an end elevation view taken along line 8-8 of FIG. 2; and,
FIG. 9 is an end elevation view taken along line 9-9 of FIG. 2.
